UNITED STATES PATENT OFFICE.

DANIEL CASSELL GRAHAM, OF PULASKI, VIRGINIA.

RAILROAD-TIE.

No. 841,242.

Specification of Letters Patent.

Patented Jan. 15, 1907.

Application filed October 16, 1906. Serial No. 339,248.

To all whom it may concern:

Be it known that I, DANIEL CASSELL GRAHAM, a citizen of the United States, residing at Pulaski, in the county of Pulaski and State of Virginia, have invented a new and useful Railroad-Tie, of which the following is a specification.

This invention relates to beds for railroads, and relates more particularly to ties made of concrete or other plastic material and to means for securing the rails to such ties.

The invention has for one of its objects to provide a tie of this character which is of simple and extremely substantial construction, designed so as to permit the rails to be easily and firmly secured thereto and of such composition as to be comparatively inexpensive to manufacture.

20 The object of the invention is the provision of fastening means for securing the rails to the ties, which means is designed with the idea of conserving to a maximum extent the strength and solidity of the ties.

25 With these general objects in view and others of a more specific character, as will appear as the description proceeds, the invention comprises the various novel features of construction and arrangement of parts,

30 which will be more fully set forth hereinafter and defined with particularity in the claims appended hereto.

In the accompanying drawings, which illustrate one of the embodiments of the invention, Figure 1 is a plan view of a portion of a railroad-track, showing a part of one of the rails and ties in section. Fig. 2 is a transverse section through one of the rails, showing the means for fastening the same to a tie. Fig. 3 is a fragmentary perspective view of a rail-tie and clamping-plate shown disassociated and in their relative positions.

Corresponding parts in the several figures are indicated throughout by similar numbers of reference.

Referring to the drawings, 1 designates the rails, which may be of the usual construction, and 2 the ties. The ties 2 are molded in a suitable form, and the composition of which 45 the ties are made consists, preferably, of one part sand, one part cement, and two parts gravel. In practice this has been found to produce a tie of great strength and hardness, and while these proportions are satisfactory 55 in certain instances they may be changed according to the requirements of any given

place. The form of the tie is preferably rectangular in transverse cross-section, with its longest dimension horizontal, and the tie is of the same transverse cross-section throughout its length. As far as the invention is concerned, however, the particular shape of the tie is unimportant. The tie is molded with a rectangular depression or socket 3 on its top surface and a slight distance inwardly 60 from each end of the tie. The depressions are located so as to lie directly under the rails 1, and in each depression is arranged a clamping-plate 4, that is held from horizontal movement with any direction by fitting snugly in the depression 70 3. By preference the walls 5 of the depression flare outwardly and the sides 6 of the plate 4 are shaped to correspond, the flare of the walls 5 serving to prevent the said walls from cracking or breaking, due to lateral strains incident to the passage of a train, such strains of course being greatest at the bends in the road-bed. The top surface of the clamping-plate 4 is cut away to form a pocket 7 for receiving the base 8 of one of the 80 rails. The pocket 7 is provided with two parallel vertical walls 9, between which the base 8 snugly engages. By having the walls 9 vertical a rail-section can be easily put in place or removed by a bodily vertical movement.

The rails are secured to the ties by means of bolts that pass vertically through the ties, one at each end thereof, through the clamping-plates, and the base of the rail. To accommodate the bolts, each tie is molded with a vertical opening disposed centrally below the depression 3. The lower end of the opening is of square cross-section, as indicated at 10, Figs. 2 and 3, and the upper portion of the 95 opening is round, as indicated at 11. The bolt 12 is of ordinary construction, having a square head which fits in the square portion 10 of the bolt-hole in the tie. The shank 13 passes upwardly through the round portion 100 11 of the hole and through an opening 14, arranged centrally in the clamping-plate 4, thence through the base of the adjacent rail. Instead of the portion 10 of the bolt-hole being square it can be of any other angular cross-section, so as to conform to the head of the bolt, the engagement of the bolt-head with the opening serving to prevent the bolt from turning. The web 15 is cut away transversely at 16 at regular intervals corresponding to the distance between adjacent ties. The base portion of the rail

is permitted to remain below the opening 16 of the web, and the base is provided with an aperture 17, through which the upper end of the bolt-shank 13 extends. The transverse opening 16 of the web 15 is large enough to receive the nut 18 and permit the same to be screwed on the bolt by means of a suitable wrench, such as a spanner or $\frac{1}{2}$ wrench. By this arrangement the rails are firmly and rigidly clamped to the plates 4 and to the ties. Since only one bolt is employed to secure each rail to a tie, the weakening of the latter is avoided to a great extent. As shown in Fig. 2, the nut 18 extends beyond the web 15 at each side, and for this reason the fish-plates at the rail-joints will be recessed to fit over the nuts, as will be readily understood.

From the foregoing description, taken in connection with the accompanying drawings, the advantages of the construction, it is believed, will be readily appreciated by those skilled in the art to which the invention appertains, so that further description thereof is deemed unnecessary, and while I have described the principle of operation of the invention, together with the apparatus which I now consider to be the best embodiment thereof, I desire to have it understood that the apparatus shown is merely illustrative and that various changes may be made when desired as are within the scope of the invention.

What is claimed is—

1. A railroad-tie made of plastic material and molded with a depression in its top surface adjacent each end and with a vertically-extending opening at each depression, in combination with a plate seated in the depression of the tie, a rail resting on the plate which is provided with an opening in its base, and a bolt extending through the tie-opening and opening of the rail for securing the rail to the tie and preventing longitudinal movement of the rail.
2. A railroad-tie made of plastic material and molded with a vertically-extending opening, in combination with a rail having an opening in its base, a bolt extending through the opening of the tie and having its threaded end uppermost, and a nut on the bolt.
3. A railroad-tie made of plastic material and molded with a depression and a vertically-extending opening at the depression, in combination with a clamping-plate seated in the depression and having an opening, a rail on

the clamping-plate and having an opening in its base, and a bolt passing through the openings of the tie and plate and through the opening of the rail for securing the rail in place.

4. A railroad-tie composed of concrete and molded with a rectangular depression having sloping walls, in combination with a clamping-plate shaped to fit in the said depression, parallel walls on the clamping-plate, a rail having its base snugly fitted between said walls and provided with a vertical opening and means extending through the plate and opening of the rail for securing the rail and clamping-plate to the tie.

5. The combination of a railroad-tie having a vertical opening, a rail having an opening in its base, and a bolt extending through the openings of the tie and rail for clamping the latter together.

6. The combination with a railroad-tie having a vertically-extending opening adjacent each end, a rail located over each opening and having its web cut away transversely and a vertical opening in the base of the rail at the cut-away portion, a plate interposed between the tie and rail, a bolt having its shank extending upwardly through the tie and plate and through the opening in the base of the rail, and a nut on the bolt disposed in the cut-away portion of the rail.

7. The combination with a railroad-tie provided with a depression on its top surface and a vertical opening at the depression which is of angular cross-section at its lower end, a clamping-plate seated in the depression and provided with spaced parallel walls, a rail having its base confined between the walls and provided with a transverse hole in the web and with a vertical opening in the base of the rail adjacent the cut-away portion, a bolt in the opening of the tie which extends through the clamping-plate and opening in the base of the rail and is held from rotation by its head engaging the angular portion of the hole in the tie, and a nut on the upper end of the bolt and arranged in the cut-away portion of the rail-web.

In testimony that I claim the foregoing as my own I have hereto affixed my signature in the presence of two witnesses.

DANIEL CASSELL GRAHAM.
